FIRE ALARM SIGNAL OR SIMILAR ARTICLE

James W. Green, Jr., New Canaan, Conn., assignor to
The Eastern Company, Naugatuck, Conn., a corpora-
tion of Connecticut

Filed Nov. 14, 1961, Ser. No. 67,516

Term of patent 14 years

(Cl. D72—1)

FIG. 1

FIG. 2

FIG. 3

FIG. 4

FIGURE 1 is a side elevational view of a fire alarm signal or similar article, showing my new design, and FIGURE 2 is a sectional view thereof taken along line 2—2,

FIGURE 3 is a top view thereof, and

FIGURE 4 is a sectional view thereof, taken along line 4—4 of FIG. 1.

The side not shown is substantially the same in appearance as the side shown, and the bottom is flat and plain.

I claim:

The ornamental design for a fire alarm signal or similar article, substantially as shown and described.
